Attorney.

UNITED STATES PATENT OFFICE.

FREDERICK J. NAGEL, OF BUFFALO, NEW YORK.

BARREL BUNG.

Application filed January 21, 1927. Serial No. 162,596.

My invention relates to barrel-bungs, and more particularly to that type in which provision is made for the escape of gases generated within the barrel.

One of the objects of my invention is the provision of a bung of the type mentioned, which is simple in construction, light in weight and reliable in action, and which will guard against the admission of air into the barrel, yet allow the escape of gases generated within the barrels.

Another object is, to provide a bung particularly adapted for use during the fermentation period of the liquid within a barrel and which is so constructed that scum rising to the surface of the liquid and eventually forced out through the bung, will have a free escape and will not clog the passages in the bung to prevent the escape of generated gases.

A still further object is, the provision of an improved bung which will assure a tight sealing of the barrel when the pressure within is less or even a trifle more than the atmospheric pressure, and wherein the escape of the gases and undesirable light matter can be controlled by an element relatively adjustable with respect to the body of the bung.

With the above and other objects to appear hereinafter, the invention consists in the novel features of construction, and in the arrangement and combination of parts to be hereinafter described, and more particularly pointed out in the subjoined claims.

In the drawings:—

Fig. 1 is a central longitudinal section of the bung.

Fig. 2 is a cross section taken on line 2—2, Fig. 1.

Fig. 3 is a cross section taken on line 3—3, Fig. 1, looking upwardly, as indicated by the arrow crossing said lines.

Fig. 4 is a central longitudinal section through the body portion of the bung, taken on line 4—4, Fig. 3, looking in the direction of the arrow crossing said line.

Referring now to the drawings in detail, the reference numeral 5 designates the body of the bung, which is longitudinally tapered in the conventional manner so that it may be driven into the usual inwardly-tapered bung-hole of a barrel. This body portion may be constructed of wood of a suitable kind, or if desired metal or other material may be used. It has an axial bore 6, provided with a large

outwardly-flaring portion 7 at its outer end, serving as a valve seat, and a smaller inwardly-flaring portion 8 at its inner end, the cylindrical intermediate portion 9, which connects said flaring portions, being of a predetermined diameter so as to properly co-operate with another part of the device, to be presently described. The inner end face of said body portion 5 is provided with radiating grooves or passages 10 which extend from the flaring portion 8 at the inner end of the bore 6 to the peripheral face of the body portion of the bung.

A closure 11 for the bore of the body portion is provided which is in the form of a pressure relief-device having a valve 12, a valve stem 13, and a grip member 14 in the form of a stem or stud extending outward axially from the valve. The valve is conical and conforms in shape and size to the inner portion of the outwardly-flaring outer end of the bore or valve seat 7, against which it is firmly seated by gravity. The valve, when seated, is therefore in a receding position and could not be taken hold of, were it not for the grip member or stud 14 extending outward axially therefrom.

The valve stem 13 is preferably cylindrical and extends through the cylindrical portion 9 of the bore 6 and through the inwardly-flaring inner end 8 of said bore, and extends a distance beyond the inner end of the body portion of the bung so that when the bung is driven into the bung-hole of a barrel, the stem will extend into the barrel. The valve stem 13 is of smaller diameter than the cylindrical portion 9 of the bore in the body portion of the bung, and consequently an annular passage 15 is provided around said stem, connecting the inner and outer flaring portions of the bore.

The valve stem 13 is threaded along its inner portion and has a baffle member 16 threaded thereon so that it may be adjusted and maintained in any desired spaced relation to the inner end of the body portion 5. This baffle member is preferably flat and circular in formation and is comparatively large in diameter, although it may be otherwise formed, and it also serves as a stop to limit the outward or unseating movement of the valve 12. A nut 17 is also threaded onto the stem of the valve and bears against the inner face of said baffle and/or stop member, and by reason of the latter being threaded onto the valve stem, said nut serves in the

capacity of a jamb-nut and guards against turning of the baffle member on said stem.

When the bung is driven into a barrel, the valve 12 will keep the barrel sealed as effectively as though an ordinary one-piece imperforate bung were used, and as barrels are invariably placed in cellars and the like, the foul or musty odors common to such places are prevented from entering the barrel and 10 contaminating the contents thereof.

As it is desirable to allow the escape of gases generated in the barrel, also the scum rising to the surface of the liquid during fermentation, a relief-device, such as provided 15 in the body portion of my improved bung, or the bung proper, will assure a clear, palatable beverage without foreign taste.

When gas is generated in the barrel and rises above atmospheric pressure, plus the 20 weight of the relief-device provided, the valve 12 will become unseated and the gases, and the scum, if any has risen to the surface of the liquid, will pass around the edge or edges of the baffle member 16 and pass 25 out through the bore 6 of the bung. The extent of outward movement of the relief-device will be in accordance with the excess pressure in the barrel, but in no case greater than allowed by the baffle or stop 30 member 16 when the latter comes in contact with the inner end of the body portion of the bung. It will be apparent, however, that when said baffle or stop member is in contact with the inner end of the body portion of the 35 bung, the gases have free escape through the radiating grooves or passages 10 formed in the inner end face of said body portion, as free access is provided to the outer ends of these grooves or passages, especially since 40 the baffle or stop member 16, being of smaller diameter than said body portion, leaves the outer ends of said grooves or passages uncovered.

Should the scum rising through the bung 45 adhere to parts thereof and cause the movable parts to stick, or even tend to act as a restraint against the free action of the movable part, it will simply be necessary to grasp the grip member or stud 14 and lift 50 the valve 12; or if the escape of generated gas is not desired at the moment, the valve may simply be rotated, when the adhering parts will become loosened.

By flaring the inner end of the bore 6 inwardly, the gases and scum have free access 55 to the annular passage 15 around the valve stem and when the valve is raised, may escape freely into atmospheric air.

Having thus described my invention, what 60 I claim is:

1. A barrel bung, comprising a body-portion having a longitudinal bore extending therethrough, a gravity valve closing the outer end of said bore and having a stem 65 projecting inwardly beyond the inner end

of said body portion, and a baffle carried by the inwardly-projecting end of said valve stem.

2. A barrel bung, comprising a body-portion having a longitudinal bore extending therethrough and grooves in the inner end face thereof extending to said bore, a gravity valve closing the outer end of said bore and having a stem projecting inwardly beyond the inner end of said body-portion, and a baffle carried by the inwardly-projecting end of said valve stem. 70

3. A barrel bung, comprising a body-portion having a longitudinal bore extending therethrough and provided with a flaring outer end serving as a valve seat, a gravity valve fitting said valve seat and having a valve stem projecting inwardly beyond the inner end of said body-portion, said valve stem being smaller than said bore to provide 80 a passage along the stem, and a baffle adjustably applied to the inwardly-projecting portion of said valve stem. 85

4. A barrel bung, comprising a body-portion having a longitudinal bore, and a passage connected at its inner end with said bore, a gravity valve closing the outer end of said bore and having a stem spaced from the wall of said bore and projecting beyond the inner end of said body-portion, and a baffle carried by the inwardly-projecting end of said valve stem and movable toward and 95 from said passage. 90

5. A barrel bung, comprising a body-portion having a bore axially therethrough provided with a flaring inner end and radial grooves in the inner end face opening at their inner ends into the flaring inner end portion of said bore, a gravity valve closing the outer end of said bore and having a stem 100 projecting inwardly through said bore and projecting beyond the inner end of said body-portion, said stem being threaded along its inwardly-projecting portion, and a baffle threaded onto the threaded portion of said stem and adjustable along the same. 105

6. A barrel-bung, comprising a body-portion having a bore axially therethrough provided with a flaring outer end serving as a valve seat, a gravity valve seated in said seat and having a stem extending inwardly through said bore and beyond the inner end of said body-portion, a baffle member adjustable on the inner end of said valve stem and normally spaced from the inner end of said body-portion, and a stud extending outward axially from said valve. 115

7. A barrel bung, comprising a body-portion having a longitudinal bore therein enlarged at its outer end to form a valve seat, a gravity valve seated against said seat in receding position, a baffle spaced from the inner end of said body-portion and connected with said valve, and a finger grip extending from the outer side of said valve. 120

8. A barrel bung, comprising a body-portion having an axial bore extending therethrough, said bore being enlarged at its outer end to form a valve seat and flared at its inner end, and the inner end face of said body portion having radiating grooves extending from the peripheral face of said body-portion to the flared inner end of said bore, a gravity valve seated against said valve seat and having a stem extending inwardly through said bore and beyond the inner end of said body-portion, said valve stem being smaller than said bore to provide

a passage around said stem and being threaded at its inner end, a baffle of smaller diameter than said body-portion threaded onto the inner end of said valve stem and adapted under certain conditions to cover the inner ends of said radiating grooves but at all times leaving the outer ends of said radiating grooves uncovered, and a nut also threaded onto said valve stem in contact with the inner face of said baffle. 15

20 In testimony whereof I affix my signature.

FREDERICK J. NAGEL.
